UNITED STATES PATENT OFFICE.

DANIEL RADOVICH AND DANIEL M. CLARK, OF MIDVALE, UTAH.

APPARATUS FOR ADDRESSING ARTICLES.

Application filed September 9, 1925. Serial No. 55,256.

Our invention relates to printing addresses on mailable articles such as magazines, periodicals, trade circulars, newspapers and office mailing literature, and has 5 for its object to provide a new and efficient apparatus for printing individual addresses directly on the article.

A further object is to provide an economical, time-saving means for printing addresses of an office mailing list on mailable matter, or similar articles.

These objects we accomplish with the apparatus illustrated in the accompanying drawings in which similar letters and numerals of reference indicate like parts throughout the several views and as described in the specification forming a part of this application and as pointed out in the appended claims.

20 In the drawings of which we have shown the best and most substantial embodiment of our invention, Figure 1 is a plan view of our apparatus. Figure 2 is a side elevation of the slug plunger. Figure 3 is an end elevation of the same at right angles to Figure 2. Figure 4 is a plan view of the slug sliding catch. Figure 5 is a side elevation of the cam roller pulley, slug plunger and press mechanism, on line 5-5 of Figure 1. Figure 6 is a section on line 6-6 of Figure 1. Figure 7 is a detail plan of the slug guide. Figure 8 is edge view of the same. Figure 9 is a plan of one side of said slug shifting bar, while Figure 10 is the other face of 35 the same.

In general, the invention consists of using linotype slugs of the desired addresses in one galley and moving said slugs individually to a printing position where the impression is 40 made and then to another galley for subsequent use, the galleries being interchangeable.

Our apparatus consists of a supporting frame A upon which the other elements of the apparatus are mounted. The said frame 45 A has a transverse supporting member B upon which the printing mechanism and galleries are mounted. Another transverse support C is provided parallel with the said supporting member B to aid in supporting 50 and carrying the slidable slug mechanism. A disk pulley 1 is operably mounted on a

shaft 2, which shaft is journaled in bearings, one of which is secured on the main frame A and the other on the said member B. The said disk pulley 1 is operated by 55 the belt 3, which, in turn, is moved by the pulley wheel 4 and the motor M. On one side face of the said disk pulley 1 is rotatably mounted a cam roller 5 on the stub shaft 6. A block 7 is secured on the said 60 support C and in said block a channel groove 8 is cut in which a sliding member 9 is carried. One portion of said sliding member 9 is bent upwardly and then backwardly 65 parallel with its main body to form a slug plunger 10 by which said slugs are pushed from the galley G to the printing position. The free end portion of the said slug plunger 10 is cut away, as at 11, to allow clearance of the slugs after they have been placed 70 in the second or receiving galley. An adjustable catch 12 is provided on the upper face of the slug plunger 10 to engage the end of each of said slugs individually and push them out of the galley on its open 75 edge. The said catch 12 is longitudinally adjustable to move different sized slugs. Lateral arms 13 and 14 are provided on the lower side of the said member 9 for engagement with the cam roller 5 on the said disk 80 pulley 1. The said arm 14 is cut away at 15 to allow the cam roller 5 sufficient clearance when its pulley 1 is rotated. Cross members 17, between which rollers 18, 19 and 20 are mounted, are provided between 85 the said frame A and the member B. Two printers' galleries G and G¹ are provided, the said gallery G is placed on top of the said rollers 18, 19 and 20, and in which are carried the address slugs S. One end of the 90 said galley G is closed, as at 16, and the other end is open; also one side is open to allow passage of the slugs therefrom. In the bottom of and near the open end of the said galleries a hole 21 is bored. A hook 22 95 for engagement in the said hole 21 is attached to a pulley cord or belt 23, and a pulley 24 is mounted on the supporting frame A over which pulley the said cord is carried. On the other end of the said cord 23, a 100 weight 25 is suspended to move the galley G and the slugs S therein longitudinally

against the slug plunger 10. The other galley G^1 is supported at one end by lugs 26 fastened on said frame A and at its other end by the member C, and on a lower plane 5 than the galley G. A lug 27 is loosely pivoted on the upper side of the said member 7 by the pin 28. A spring 29 is fastened to the said member 7 and engages with the hole 30 in one edge of the said lug 27 to normally 10 hold said lug parallel with said member 7 but to allow the slugs to be moved along the side of said lug. A block 31 is secured to one of the said members 17 by the thumb screws 32 and is slidably and adjustable 15 longitudinally in the slot 33. Another smaller block 34 is secured to one side of the said block 31 to limit the longitudinal movement of a slidable L-shaped member F, shown in detail in Figures 9 and 10, and 20 which is made of a flat bar 36 to which a cross bar 37 is secured and the said L-shaped member is supported at one end on the member 7 and is slidably mounted between the guides 38, which are secured to a cross member 39, which, in turn, is mounted at one 25 end to the main frame A and at the other end on the support C. A spring 40 is secured to the lower side of the said L-shaped member F, for holding it against the block 34 while the slug is being pressed for printing the desired address. A pressing lever 41 is pivoted at one end to the main frame A by the pivot 42 and on the other end of the 30 said lever 41 a block 43 is adjustably mounted and it acts as the press block when the printing is being done. A hole 44 is bored through the said lever and in which a rod 45 is operable and on which a spring 55 is carried. Another hole is bored through the 35 member C of the support directly in alignment with the said hole 44 of the lever 41. A lever 46 is pivotally mounted at one end to the said frame A by the pivot pin 47, and on the other end of the said lever 46 a projecting lug 48 is provided for engagement 40 with the said cam roller 5 on the said pulley wheel 1. The said rod 45 is connected with the lever 46 by the pin 49. The said bar 36 has an angled guide strip 50 secured on 45 one face thereof, which strip 50 engages with a pin 51 projecting laterally from the inner face of said member 9 to move the said slugs into the galley G^1 after the address desired has been printed.

50 The operation of our device is as follows: When the slugs are placed in the galleys, a full galley G is placed in the machine and an empty one G^1 is placed on the other side to receive the slugs after they have been used 55 to print. With the slugs against the side face of the slug plunger 10 on the sliding member 9, the machine is ready for operation. The motor M is turned and the pulley wheel 4 turns the belt 3, which, in turn, rotates the disk pulley 1. The cam roller 5

rotates with the pulley 1, which roller comes into contact with the arm 13 of the slidable member 9 and pressing against said arm 13 moves the slidable member 9 longitudinally; with the movement of the member 9 and its 70 component parts the catch 12 engages one of the slugs and slides it longitudinally from one galley until it is in direct alinement with the end of the other galley, and is directly under the press lever 43. The operator then 75 places the matter to be addressed over the slug and holds it there. As the disk pulley 1 rotates, the cam roller 5 disengages from the arm 13 and comes into contact with the lug 48 on the lever 46, and as the disk pulley 1 continues to rotate and with the cam roller 5 in contact with the lever 46, the said lever will be lowered and pull the press lever 43 downwardly and press the article 80 firmly against the letters of the slug. The continued rotation of said pulley 1 will release the said lever 46, and the spring 55 will raise the press lever 43. The cam roller will engage the arm 14 and move it, 85 with its connections, away from the shaft 2. The tension of the spring 40 will move the L-shaped member F into contact with the block 34, and the slug plunger 10 will also be moved away from said shaft 2 and far enough that the catch 12 will be slid by the 90 next slug and assume a position at the rear end of said slug in the galley G, at the same time the bar 36 will be moved by the engagement of pin 51 in member 9, and the angled strip 50 will move the used slug onto the galley G^1 . The slugs in the galley G are to be inked as often as required by running the conventional ink roller over them.

Having thus described our invention and its operation we desire to secure by Letters 105 Patent and claim:

1. An apparatus for addressing articles comprising a frame; a power driven disk pulley; a roller carried on the side face of the disk pulley; printer's slugs carried on said frame; a slug plunger having depending arms thereon, adapted to be engaged by said roller; an adjustable catch on the upper face of said slug plunger; adapted to engage the end of each of said slugs individually, and push them out of the galley in which they are carried; a lever pivoted to said frame and adapted to be engaged by said roller to press the article to be addressed against the slugs in the printing position, means to move said slugs from the printing position to an adjacent galley, said means consisting of a bar 36 and an angle strip thereon, and a pin projecting from the inner face of a portion of the slug plunger, to move said catch laterally.

2. An apparatus for addressing articles comprising a frame; a power driven disk pulley mounted thereon; a roller mounted on said pulley; a lever movable on its pivot 130

by said roller; a slug plunger carried on said frame, and having depending arms thereon; a catch on the upper portion of said plunger adapted to move said slugs individually from one galley to a printing position, and to move a preceding slug into another galley; a galley support mounted on said

frame; printer's slug with characters thereon forming an address and carried in said galleys.

In testimony whereof we have affixed our signatures.

DANIEL RADOVICH.
DANIEL M. CLARK.
